UNITED STATES PATENT OFFICE

133,865

DESIGN FOR A PRINTED RUG OR THE LIKE

John Stout, Fox Chase, Pa., assignor to Carthage
Mills Incorporated, Cincinnati, Ohio, a corpora-
tion of Ohio

Application June 22, 1942, Serial No. 107,295

Term of patent 7 years

To all whom it may concern:

Be it known that I, John Stout, a citizen of the United States and a resident of Fox Chase, in the county of Philadelphia and State of Pennsylvania, have invented a new, original, and ornamental Design for a Printed Rug or the like, of which the following is a specification, reference being had to the accompanying drawing, forming a part thereof.

The drawing is a plan view of one end of a rug showing my new design comprising a main design portion and border elements. The main design portion and the side border elements are

repetitive in character throughout the extent of the printed rug, which is terminated on its opposite end by a repetition of the end border. The opposite end of the rug, exclusive of the end border, is finished by a repetition of only that half of the main design which lies adjacent the end border in the drawing. When this is done, one of the Indian headdresses will lie inside the border at each corner of the completed rug.

I claim:

The ornamental design for a printed rug or the like, as shown and described.

JOHN STOUT.
